APPARATUS FOR ACTUATING THE CORES OF A DIE CASTING MACHINE

Application filed February 15, 1930. Serial No. 428,558.

This invention relates to apparatus for actuating the cores of a die casting machine, and more particularly to a hydraulically actuated attachment for die casting apparatus to separate the cores thereof from the cast metal parts.

An object of this invention is to provide simple and efficient apparatus for withdrawing the cores of a die casting machine from the cast articles.

In accordance with this object, one embodiment of the invention comprises a die section having cores slidably mounted in the casting cavities thereof, portions of the cores being shouldered and confined within recesses of the die section for limiting the longitudinal movement of the cores. Bearing members are mounted within the central portions of the die section for receiving the inner ends of levers which extend through apertures in the cores and to the lateral edges of the die section. A plurality of hydraulically operated plungers are mounted adjacent to the lateral edges of the die section and connected to the outer extremities of the levers for actuating the cores to withdraw them from the cast metal parts.

A clear understanding of the invention will be had from the following description of one specific embodiment thereof when taken in connection with the accompanying drawings, wherein

Fig. 1 is a perspective view of a stationary die section and the hydraulic piston structure for actuating the cores thereof;

Fig. 2 is a longitudinal cross-sectional view of the pistons and die section taken through a pair of the cores thereof, and

Fig. 3 is a central cross-sectional view of a telephone transmitter shell which is one of the cast parts in connection with which the core actuating structure is adapted for use.

Referring now to the drawings in which like reference numerals designate similar parts throughout the several views, there is disclosed a rectangular die shoe 5, and a stationary die section or die block 6 is shown secured thereto by means of countersunk bolts 7, and it is the purpose of this invention to provide an actuating structure for

moving the cores 8 thereof to separate them from the cast, cooling metal as it starts to shrink.

The metals enters through a central aperture or gate 9 and passes through channels 10 into symmetrically positioned casting cavities adjacent the cores 8. The cores 8 are constructed of metal or other suitable material and are slidably mounted within suitable apertures extending downwardly through the diehalf or block 6, and the lower or outer extremities of the cores 8 have shoulders 11 which are confined within recesses 12 formed in the lower portion of the diehalf or section 6 and the upper part of the die shoe 5 for limiting the longitudinal movement of the cores. In the specific embodiment shown, the cores 8 and the surrounding casting cavities are shaped to mold the lower or larger flanged portion of a telephone transmitter shell 13 (Fig. 3), although the invention may of course be applied to the casting of parts of various shapes. The cores are slidably mounted within the diehalf so that they may be moved or withdrawn from the casting 13 when the cast metal starts to cool and shrink. A pair of transverse slots 14, only one of which appears in Fig. 2, are provided in the lower portion of the diehalf 6 extending between the lateral edges thereof and through the foremost and the farthestmost pairs of cores 8.

Since the mechanisms associated with each of the slots 14 are identical, only one such mechanism will be described. A bearing member 15 is positioned within each slot 14 in the central portion of the diehalf and between the cores 8, the member being secured therein by means of a set screw 16. A pair of rectangular levers or connecting rods 19 provided with rounded inner ends which are pivotally mounted in the bearing member 15 extend outwardly through the die block slot 14 through beveled apertures 20 provided in the cores 8. Member 15 is provided with upper and lower rounded projections 17 and 18, respectively, against which the inner ends of levers 19 bear in rolling contact when the levers are actuated.

A plurality of cylindrical guide blocks 23

are secured by screws 24 to the die shoe 5 adjacent the lateral sides of the diehalf 6 and the outer ends of the levers 19, and on the upper ends of the guide blocks, cylinders 25 are secured by means of bolts 27 passing through plates 26 which serve as cylinder heads. Pistons 28 are provided within the cylinders 25 and piston rods 29 with crossheads 30 integral with the lower ends thereof are bolted to the pistons 28. Wrist pins 31 connect the crossheads 30 with the levers 19, the guide blocks 23 having suitable lateral slots 21 aligned with the slots 14 to permit vertical movement of the levers 19.

15 The piston rods 29 are provided with suitable packing material 32 which is adjustably housed within the upper ends of the guide blocks 23 by means of threaded bushings 33, slots 34 (Fig. 1) being provided in the guide blocks to enable the operator to adjust these bushings by inserting a pin through the slots 34 and into engagement with peripheral recesses 46 provided in these bushings.

Lower and upper conduits 35 and 36, respectively, extend into the upper and lower ends of each cylinder 25 to enable the pistons 28 and the metal cores 8 to be operated in either direction by means of fluid pressure. As shown in Fig. 1 the conduits 35 and 36 are connected respectively to upper and lower sets of pipes 38 and 39 which lead to a four-way valve 40 of any suitable construction for controlling the operation of the pistons, this valve being connected to a suitable source of fluid or oil pressure (not shown) by means of pipes 41. When a manually operated handle 42, connected to the valve 40 and fulcrumed at 43, is moved upwardly, fluid pressure is applied to the set of pipes 38 and exhausted from the set 39 to move the pistons 28 downwardly, and when the handle 42 is moved downwardly, fluid under pressure is forced into the set of pipes 39 and exhausted from the set 38, thus causing the pistons to move upwardly. Four guide pins 37 extend upwardly from the diehalf 6 to cooperate with corresponding recesses formed in the other diehalf (not shown) when the castings are being formed.

50 In the operation of the above described apparatus, a movable upper diehalf or die block (not shown) is brought down over the guide pins 37 and into contact with the lower diehalf 6, and the molten metal is injected through the central gate 9 and into the channels 10 and the casting cavities surrounding the die cores 8, which form the lower or larger portion of the aluminum telephone transmitter shell 13 (Fig. 3). As the cast metal starts to cool and shrink around the cores 8, oil or other suitable motive fluid is forced into the conduits 36 by moving the hand lever 42 of the four-way valve 40 about the fulcrum 43 as aforescribed, thus forcing the pistons 28 and the levers 19 downwardly,

and the cores 8 will thereby be moved downwardly and away from and out of contact with the cast parts 13, and separating each of the cores 8 from the cast parts as they start to cool and shrink. This described position of the mentioned parts is shown in Fig. 2 with the cast-parts 13 removed from the casting cavities. In case thin piece parts or castings are being made, which will cool relatively faster than heavy parts, this core actuating operation is set up in a comparatively short time after the parts are cast, and it will be understood that the dimensions of the cast parts may to a considerable extent be controlled by the time of withdrawing the cores. By means of the above described manual control, the operation of the machine is made more flexible than in the case of core-pulling mechanism which is automatically operated at a predetermined time in the cycle of operation of the diecasting machine.

It will also be understood that the hydraulic pressure mechanism hereby provided serves to withdraw the cores smoothly and to move them approximately simultaneously, but if some of the cores stick or set up more resistance than others the pressure will in a short time increase sufficiently on the pistons actuating such sticking cores to remove them shortly after the more easily actuated cores are withdrawn. With the cores thus removed from the cast parts, the parts are removed by withdrawing the upper diehalf (not shown) away from the guide pins 37, and ejecting apparatus (not shown) is then set in operation to remove the castings. When the next set of transmitter parts is to be cast, oil under pressure is released into the ports 35 by moving the hand lever 42 downwardly as aforescribed to move the pistons 28 and the cores 8 upwardly into position for receiving and forming the molten metal into the transmitter shells 13, whereupon the upper diehalf is again brought down into engagement with the die block 6 to receive another charge of metal, and the casting process then goes on as aforescribed.

105 In case it is found that one of the cores 8 is raised by its corresponding piston to a position higher than its proper casting position, a shim 45 (Fig. 2) may be placed above the corresponding piston 28 to limit the upward movement of both, and thus it will be understood that the casting position of any one of the pistons may be similarly adjusted with respect to the die plates.

110 From the foregoing description, it is believed to be obvious that the hydraulic operating piston and lever structure provided by this invention comprises an efficient and simple apparatus for withdrawing the cores from the cast parts.

115 It is, of course, to be understood that the invention is not to be limited to the specific 120

embodiment herein described and illustrated, but is to be limited only by the scope of the annexed claims.

What is claimed is:

- 5 1. In a casting apparatus, a base, a mold part mounted thereon having a casting cavity, an apertured core reciprocably mounted within the cavity, a lever extending through the aperture in the core and fulcrumed at one end within the base, and means operatively connected to the lever for moving it about its fulcrum to cause an inserting and retracting movement of the core relative to the casting cavity.
- 10 15 2. In a casting apparatus, a base, a mold part mounted thereon having a casting cavity, an apertured core reciprocably mounted within the cavity, a lever extending through the aperture in the core with one end pivoted within the base at one side of the core, the aperture in the core formed to permit a rocking motion of the lever therein, and means operatively connected to the opposite end of the lever for moving the lever about its pivot 20 to cause an inserting and retracting movement of the core relative to the casting cavity.
- 25 3. In a casting apparatus, a base, a mold part mounted thereon having a casting cavity, an apertured core reciprocably mounted within the cavity, a lever extending laterally through the aperture in the core with one end fulcrumed within the base at one side of the core, and fluid operated means operatively connected to the opposite end of the lever for moving the lever about its fulcrum to cause an inserting and retracting movement of the core relative to the casting cavity.
